Specification for Design.

Patented Nov. 22, 1921.

Application filed April 19, 1921. Serial No. 462,706. Term of patent 3½ years.

To all whom it may concern:

Be it known that I, AUGUST J. ROTH, a citizen of the United States, residing at Mount Vernon, Westchester county, State of New York, have invented a new, original, and ornamental Design for a Handle or Similar Article of Manufacture, of which the following is a specification, reference being had to the accompanying drawing, forming a part thereof.

In said drawing:

Fig. 2 is a plan view thereof.

I claim:

The ornamental design for a handle or similar article of manufacture, substantially as shown.

AUGUST J. ROTH.
